UNITED STATES PATENT OFFICE.

JOHN EVANS, OF ETNA, PENNSYLVANIA, ASSIGNOR OF ONE-HALF TO
GEORGE A. CHALFANT, OF SAME PLACE.

BRICK NOZZLE FOR GAS-FURNACE PIPES.

SPECIFICATION forming part of Letters Patent No. 296,398, dated April 8, 1884.

Application filed June 1, 1883. (No model.)

To all whom it may concern:

Be it known that I, JOHN EVANS, of Etna, in the county of Allegheny and State of Pennsylvania, have invented a new and useful Improvement in Gaseous-Fuel Furnaces; and I do hereby declare the following to be a full, clear, and exact description thereof, reference being had to the accompanying drawings, forming part of this specification, in which—

10 Figure 1 is a longitudinal sectional view of a puddling-furnace, showing the application thereto of my improvement. Fig. 2 is a horizontal section on the line *x* of Fig. 1.

Like letters of reference indicate like parts 15 in each.

Difficulty has heretofore been experienced in that class of furnaces in which gas is used, and particularly natural or hydrocarbon gas from the earth, on account of the burning of 20 the ends of the pipes which supply the gas to the furnace. The pipes must be led to the burning-point, which is usually at or near the bridge of the furnace, and consequently their ends are exposed to the intense heat of the 25 furnace and burn off rapidly, producing inequality in the heat, irregularity in the action of the furnace, leakage of air into the furnace, and leakage and waste of gas. To obviate all 30 of these disadvantages I lead the gas into the furnace by means of thick pipes or nozzles *a*, made of fire-clay or other refractory material, which are built into the wall *b* of the furnace, and project into the vertical air flue or flues *c*, to a point at or near the bridge *d*. These 35 pipes or nozzles have a central channel, *a'*, of

the proper size for the passage of the gas. The front ends are preferably beveled or pointed, as at *a'*, so as to interfere as little as need be with the draft of the furnace. The rear ends have a socket, *a*, of larger diameter than that 40 of the channel *a'*, for receiving the ends of the branch pipes *e* of the gas-main *e*. The joints between the pipes *a* and *e* are made tight by packing or cement, as at *g*. Being 45 thick, strong, and fire-resisting by nature, the gas nozzle is not affected injuriously by the heat to which it is exposed. The pipes *e*, not being exposed at all to the heat of the furnace, do not burn out. Another advantage is that the gas 50 main and pipes can be removed and replaced without injuring or in any way disturbing the walls of the furnace.

What I claim as my invention, and desire to secure by Letters Patent, is—

In furnaces for burning gaseous fuel, the 55 combination, with the air-flue and bridge-wall, of the refractory gas-induction nozzles arranged in the furnace-walls and projecting into the air-flue to a point at or near the bridge-wall, said nozzles having beveled delivery ends and sockets for the reception of the gas-supply pipes, substantially as and for the purposes specified.

In testimony whereof I have hereunto set my hand this 31st day of May, A. D. 1883.

JOHN EVANS.
